US0D1073045S

(12) **United States Design Patent** (10) **Patent No.:** **US D1,073,045 S**
(45) **Date of Patent:** **** Apr. 29, 2025**

(54) **PORTABLE FAN**

(71) Applicant: **Guangdong Aoyun Technology Co., Ltd.**, Guangdong (CN)

(72) Inventor: **Xueping Zhu**, Guangdong (CN)

(73) Assignee: **Guangdong Aoyun Technology Co., Ltd.**, Guangdong (CN)

(**) Term: **15 Years**

(21) Appl. No.: **29/982,241**

(22) Filed: **Jan. 6, 2025**

(30) **Foreign Application Priority Data**

Dec. 30, 2024 (CN) 202430835659.3

(51) **LOC (15) Cl.** **23-04**

(52) **U.S. Cl.**

USPC **D23/370**

(58) **Field of Classification Search**

USPC D23/370, 381, 382

CPC F04D 29/002; F04D 29/40; F04D 29/403;

F04D 29/00

See application file for complete search history.
